INVENTOR

BY Victor J. Evans

ATTORNEY

UNITED STATES PATENT OFFICE

JASON DANIEL KINSLEY, OF CEDAR RAPIDS, IOWA

RAZOR BLADE HOLDER

Application filed April 10, 1928, Serial No. 268,958. Renewed June 30, 1931.

This invention relates to improvements in razors and has for an object the provision of a holder which will accommodate either a single or double edged razor blade, so that the former may be used after the manner of an ordinary straight handle razor, and will also provide convenient means for holding the blade for the purpose of stropping or honing.

10 Another object of the invention is the provision of a holder of the above character which may also be used in connection with a blade guard, so that the razor may be used as a safety razor when desired.

15 Another object of the invention is the provision of novel means for clamping the blade in position for use, the construction providing a simple, cheap and efficient blade holder which possesses all of the combined advantages of the old style straight razor and the modern safety razor.

With the above and other objects in view, the invention further includes the following novel features and details of construction, to 25 be hereinafter more fully described, illustrated in the accompanying drawings and pointed out in the appended claims.

In the drawings:—

Figure 1 is a plan view showing the blade holder in open position.

Figure 2 is a perspective view of the holder with a single edged blade in position, the clamping arms being unlocked.

Figure 3 is a longitudinal sectional view 35 of the razor with a blade in position and the arms locked against pivotal movement.

Figure 4 is an enlarged sectional view on the line 4—4 of Figure 3.

Figure 5 is a detail plan view of a single 40 edged blade.

Figure 6 is a plan view illustrating a double edged blade with the guard in position for use, a portion of the handle being broken away.

Figure 7 is an enlarged sectional view on the line 7—7 of Figure 6.

Figure 8 is a detail plan view looking at the outer wall of the guard.

50 Referring to the drawings in detail where in like characters of reference denote corre-

sponding parts, the reference character 10 indicates the handle of the razor, which as shown in Figure 2, is provided with a longitudinal slot 11 and pivotally and slidingly secured to one end of the handle is a clamping arm 12. The arm 12 is provided with an elongated slot 13 through which a pin 14 passes so that the arm will be slidingly and pivotally connected to the handle. Pivotally secured to the outer end of the arm 12 as shown at 15 is one end of an arm 16, while the free end of this arm is provided with a slot 17 which opens at its outer end. By reference to Figure 1 of the drawings it will be seen that the arm 16 may be swung inward over the arm 12 so that the slots 13 and 17 will register and by moving the arms inward, the inner end of the arm 16 will be engaged over a pivot 14 so that relative pivotal movement of the arms 12 and 16 will be prevented. The inner end of the arm 12 is provided with an offset extremity 18 which has a yielding engagement with a notch 19 provided in one of the walls of the slot 11 of the handle. The notch 19 is so positioned with respect to the pivot 14 that when the arms are moved to their limit of inward movement, this offset extremity 18 will engage within the notch.

The arms 12 and 16 are adapted to have 50 clamped between them a single edged blade 20 or a double edged blade 21. For this purpose the blade 20 is provided with spaced openings 22 for the reception of inwardly offset portions or studs 23 provided upon the arm 12. Openings 24 are provided in the other arm.

When the blade 20 is secured in position, the razor may be used after the manner of an ordinary straight handle razor, either 55 when shaving or stropping. The blade 20 is provided at one end with a notch 25 to accommodate the pivot pin 15.

The double edged blade 21 may be secured 60 between the arms 12 and 16 in the same manner as the blade 20. The blade 21 may be of the type used in connection with the Gillette razor and these blades are provided with openings 26 and the offset portions or studs 23 of the arm 12 are so spaced that 65

two of these studs will enter a single opening 26. The blade 21 may be stropped or honed when in this position.

If desired, a guard may be positioned over the blade 21. This guard consists of a convex outer wall 27 whose opposite edges are cut away as shown at 28 so as to permit the edges of the blade to extend beyond the edges 29 of the guard. Extending inwardly and spaced from the wall 27 are flanges 30 whose outer edges are spaced to provide guard teeth 31 and whose inner edges are spaced apart to slidably receive either of the arms 12 or 16 between them. This is clearly illustrated in Figure 7 of the drawings. The space between the flanges 30 and the inner face of the wall 27 provides grooves 32 which receive the opposite edges of the blade 21.

The invention is susceptible of various changes in its form, proportions and minor details of construction and the right is herein reserved to make such changes as properly fall within the scope of the appended claims.

Having described the invention what is claimed is:

1. A razor comprising a handle, a blade clamping arm having, in one end, a longitudinal slot closed at both ends, a pivot pin upon one end of the handle engaging in said slot whereby to pivotally and slidably connect the arm with the handle, a second blade clamping arm swiveled at one end to the other end of the first mentioned arm and formed, in its other end with a slot opening through said end whereby, when the arms are in overlapped relation, to clamp a blade between them, and are shifted with respect to the pivot pin, the arms will be held against relative swinging movement, the said handle having a notch spaced inwardly from the pivot pin, the first mentioned blade clamping arm having its end at which the slot is located offset on a curved line and its edge rounded at each side and tapered to engage, at its extremity, in the said notch.

2. A razor comprising a handle, a pair of clamping arms connected together at one end, a blade adapted to be clamped between said arms, means providing an interlocking engagement between the handle and the arms to hold the later in clamping position, a guard embodying a wall having an outer convex surface, said wall being integral with inwardly extending flanges, said wall and flanges being divided at their outer edges for a distance equal to the length of a double edged razor blade and adapted to receive and impinge upon the sides of said blade when inserted, each of said flanges being provided along its outer longitudinal edge with a series of guard teeth for a distance equal to the length of the blade edge, for the purpose of protecting the face from being injured while shaving, said flanges having their opposed inner edges spaced apart to receive a

blade clamping arm, and the said wall on the opposite side of the blade being of such width and adaptation as to cover all but a narrow margin of the blade along each of its cutting edges, and to provide a surface giving a smooth feeling to the face of the user, and which in combination with the guard teeth provide means for holding the skin in correct relation with the blade edge for shaving purposes, said toothed guard being slidably attached and detachable to said blade by the impinging action of the guard, the same being guided to place by the guard-space receiving the blade clamp, and being held in place by the impinging action of the guard against any flexation apart of the blade clamping arms.

In testimony whereof I affix my signature.
JASON DANIEL KINSLEY.
